CLAIM

The ornamental design for a pendant generator for dendriform graphic patterns, substantially as shown and described.

DESCRIPTION

FIG. 1 is a side elevational view of a pendant generator for dendriform graphic patterns showing my new design;

FIG. 2 is a side elevational view thereof taken from another side;

FIG. 3 is a top plan view thereof;

FIG. 4 is a bottom plan view thereof; and

FIG. 5 is an enlarged elevational view of the lower portion.

FIG. 1

FIG. 3

FIG. 2

FIG. 4

FIG. 5
